Patented Aug. 22, 1922.

UNITED STATES PATENT OFFICE.

OLAF STENSON, OF CHICAGO, ILLINOIS, ASSIGNOR TO WESTERN ELECTRIC COMPANY,
INCORPORATED, OF NEW YORK, N. Y., A CORPORATION OF NEW YORK.

WIRE-BENDING MACHINE.

1,426,790.

Specification of Letters Patent. Patented Aug. 22, 1922.

Application filed January 7, 1920. Serial No. 349,967.

To all whom it may concern:

Be it known that I, OLAF STENSON, a citizen of the United States, residing at Chicago, in the county of Cook, State of Illinois, have invented certain new and useful Improvements in Wire-Bending Machines, of which the following is a full, clear, concise, and exact description.

This invention relates to special tools and machinery and more particularly to wire-bending apparatus and it has for its object to provide a simple, convenient and efficient machine for bending to the required form a plurality of supporting wires extending from a carrying member of insulating material used in vacuum tubes or electric light bulbs. To these and other ends the invention resides in certain improvements and combinations of parts which will be herein-
after more fully described, the novel features being pointed out in the claims at the end of the specification.

In the drawings:

Figure 1 is a top view of a bending machine constructed in accordance with and illustrating one embodiment of my invention;

Figure 2 is a section taken substantially on the line 2—2 of Figure 1;
Figure 3 is a detail fragmentary perspective view of the seat in which the workpiece is held;

Figure 4 is a top view partly in horizontal section shown the parts in a position different from that shown in Figure 1, the operating handle being partly broken away;

Figure 5 is a fragmentary detail section taken in the same plane as Figure 2 but showing the rotary die at the conclusion of its operation; and

Figure 6 is a perspective view, partly broken away, of the vacuum tube in the manufacture of which the apparatus is used.

Similar reference numerals throughout the several views indicate the same parts.

Referring first to Figure 6 A indicates a rectangular block of insulating material, usually made of the commercial substance Lava-lite, which is held by clips B near the head of the tube C. Proceeding laterally therefrom and carried thereby are two wires D that support the grid E while from the underside projects a relatively transverse wire F that is formed into a hook to support a filament G. The function of the present machine is

to form this hook F and to also give the proper angular form to the wires D.

Referring to the other figures, two associated blocks 1 and 2 form the bases for a fixed die 3 and a movable die 4. The fixed die has a raised center provided with a rectangular seat 5 best shown in Figure 3 and of dimensions to snugly accommodate the block A. In the present instance, the said block is supported therein by its lateral wires D extending through lateral slots or openings 6 in the seat, while the bottom wire F extends through a slotted opening 7 in the bottom of the seat. From the region of the seat, the die faces of the die member 3 extend rearwardly and laterally as shown. The movable die 4 is of complementary form and is provided with a central recess 8 to receive the seat 5 and the workpiece as the two elements come together. It is carried on a ram 9 operating in a T-slot guide 10, in the block 2 and its rear end is bifurcated, as shown in Figure 2, to receive an operating lever 11 slotted at 12 to take a pin 14 on the ram, the operating lever being pivoted to the block at 15. Projecting from the recess 8 of the die element 4 is a yielding plunger 16 slideable in a bore 17 in the ram from which it is normally projected by a coil spring 18. It is further guided and prevented from turning by a transverse pin 19 extending through a slotted portion 20 of the plunger. As the dies come together or just prior to the contact of the movable die 4 with the wires D of the workpiece, this plunger 16 cooperates with the block A and clamps it in place with a yielding pressure. The normal position of the parts just after the workpiece has been inserted is shown in Figure 1 and the completion of the forming operation is illustrated in Figure 4.

The above described clamping action of the die 4 and its attachments is utilized to hold the workpiece while the wire F is being acted upon by forming mechanism that I will now describe. The fixed die 3 is formed with extensions 21 by means of which it is fixed in the block 1 with pins 22. At an intermediate point, the extensions provide a bearing for a shaft 23 upon which turns a rotary die 24 having an operating handle 25. The die is slotted transversely at 26 through its axis as is the shaft 23 on which it turns so that a flat working face is formed on a chord of the circle on which the

die member swings, which face is spaced from the axis a distance equal to the thickness of the wire F.

- A longitudinal recess or groove 27 runs through the extension 21 and the shaft 23 to accommodate a sliding mandrel 28 of the form shown in Figures 2 and 4. This mandrel lies with one edge coincident with the turning axis of the die and it is formed, in the present instance, by an extension on a plunger 29 arranged in alignment with the shaft 23 and movable endwise by means of a knob 30 within the limits prescribed by a pin 31 engaging in a cutaway portion 32 thereof. With the movements of the plunger between the dotted and full line positions of Figure 1, the mandrel 28 is operated into and out of a position in which it intersects the slot 26 and crosses above the wire F.
- In operation, the ram 9 is held in the position of Figure 4 to clamp the workpiece in its seat and the mandrel 28 is pushed into the operative position of Figure 4. By means of its handle 25, the rotary die 24 is then moved from the position of Figure 2 to that of Figure 5. The face of the die thus swings around the axis, and the end of the wire F which initially laid straight along the face of the die, is bent around the mandrel 28 into the hooked shape shown in Figure 5. The die 24 is returned to its normal position against a stop pin 33 and the mandrel 28 withdrawn longitudinally by means of the knob 30, while the ram 9 is also withdrawn to the position of Figure 1 to release the block A. The latter may now be removed in the manner in which it was inserted as the hooked end of wire F is free to pass through the slot 26 in the die and through the opening 7 provided in the seat 5 of the die 3.

I claim as my invention:

1. In a wire bending machine, a die member comprising a base, horizontally slotted vertical members projecting therefrom, said members and slots being arranged to provide a seat for a workpiece having wires extending therefrom, a ram mounted for horizontal reciprocation toward and away from said die member and carrying a second die member adapted to form the wires of said workpiece around the rear walls of said slots and against said vertical members.
2. In a wire-bending machine, the combination with a die member provided with a seat for the workpiece having horizontal slots to accommodate wires extending therefrom, of a ram mounted for horizontal reciprocation toward and from the seat and carrying a die member adapted to form the wires against the first mentioned die member and a yielding clamping member on the ram adapted to engage and hold the workpiece as the dies go into effect.
3. In a wire bending machine a die mem-

ber comprising a base, horizontally slotted vertical members projecting therefrom, said members and slots being arranged to provide a seat for a workpiece having wires extending therefrom, a ram mounted for horizontal reciprocation toward and from said die member and carrying a second die member adapted to form the wires around the rear walls of said slots and against said vertical members, said die member on the ram being recessed to receive the vertical members of said first die member.

4. In a wire bending machine, the combination with a die member provided with a raised center having a cavity therein forming a seat for the workpiece, said cavity having horizontal slots to accommodate wires extending therefrom, of a ram mounted for horizontal reciprocation toward and from the seat and carrying a die member adapted to form the wires against the first mentioned die member, said die member on the ram being recessed to receive the raised portion of the other and a yielding clamping member on the ram normally projecting from the recess to engage and hold the workpiece as the dies go into effect.

5. In a wire bending machine, the combination with a shaft having a rotary bending die mounted thereon, said shaft and die having aligned transverse slots therein extending through their axis, of a longitudinally retractable mandrel intersecting the slot.

6. In a wire bending machine, the combination with a rotary bending die having a transverse slot therein extending through its axis, of a longitudinally movable mandrel intersecting the slot and having one edge coincident with the axis of said die.

7. In a wire bending machine, the combination with a shaft having a longitudinal recess therein and a longitudinally movable mandrel in the recess having one edge coincident with the axis of the shaft, of a rotary bending die mounted on the shaft.

8. In a wire bending machine, the combination with a shaft having a longitudinal recess therein and a rotary bending die mounted on the shaft, said die and shaft being provided with aligned transverse slots, of a longitudinally movable mandrel operating in the recess of the shaft to extend parallel with the axis of the latter.

9. In a wire bending machine, the combination with a die member provided with a seat for the workpiece having lateral openings therein to accommodate wires extending laterally from the workpiece, and an opening in its bottom to accommodate a third wire extending transversely to the others, of a ram movable toward and from the seat and carrying a die member adapted to form the lateral wires against the first mentioned die member, a mandrel adapted to support said third wire and a rotary die

for bending the latter around the mandrel.

10. A wire working machine adapted to operate upon a workpiece having a plurality of wires projecting therefrom, said machine comprising a holder for said workpiece, a reciprocating member for forming one of said wires around said holder, a mandrel carried by said holder, and a rotary member for forming another of said wires around 15 said mandrel.

11. In a wire bending machine, a die member comprising a base, vertical members pro-

jecting therefrom, one of said members being horizontally slotted, said members and slot being arranged to provide a seat for a 15 workpiece having a wire extending therefrom, a ram mounted for horizontal reciprocation toward and away from said die member and carrying a second die member adapted to form the wire of said workpiece.

20
In witness whereof, I hereunto subscribe my name this 30 day of December A. D., 1919.

OLAF STENSON.
